UNITED STATES PATENT OFFICE.

JONATHAN CRABTREE, OF PHILADELPHIA, PENNSYLVANIA, ASSIGNOR TO JOHN GAY, OF SAME PLACE.

DESIGN FOR A CARPET-PATTERN.

Specification forming part of Design No. 5,472, dated January 16, 1872.

SPECIFICATION.

I, JONATHAN CRABTREE, of the city of Philadelphia and State of Pennsylvania, have invented a new and original Design for Carpets, of which the following is a specification:

The nature of my design is fully represented in the accompanying photographic illustration, to which reference is made.

I claim as my invention—
The design for a carpet, as shown.
October 28, 1871.

JONATHAN CRABTREE.

Witnesses at signing:

JAMES H. GAY,
HUGH MCMURTRIE.
